UNITED STATES PATENT OFFICE.

FREDERICK W. KASSLER, OF ST. LOUIS, MISSOURI.

COIN-CONTROLLED LOCK.

Application filed December 29, 1925. Serial No. 78,206.

The present invention relates to improvements in coin controlled locking mechanism, and is peculiarly adapted for application to a door or other swinging closure such as is commonly employed to guard the entrance to pay-as-you-enter compartments. However, the lock is capable of a wide and varied field of utility and may be associated with swinging closures, sliding closures, and other types of doors, box covers, vending machines, etc.

One object of the invention is to provide a lock in which the last coin inserted will be visible at the exterior of the lock until the lock is subsequently operated by another coin. Thus, when the lock is used to control pay-as-you-enter compartments, a spurious coin will be visible to an attendant during the time that the person passing the coin is in the booth or compartment controlled by the lock.

A further object of the invention is to provide a novel method of attaching the lock casing to a door, in such a manner that it cannot be removed from the outside of the door by the use of screw drivers or similar tools. More specifically the attaching screws for the lock casing are concealed and housed by the plate which covers the coin compartment, this plate being retained in place by a key operated locking mechanism, and being removable to expose the screws only by one possessing the proper key.

A further object of the invention is to provide a lock of this character which is so constructed that a coin cannot be lost by improper turning of the handle knob. In other words, the coin is always in operative position until the door controlled by the lock has actually been opened.

Another object of the invention is to provide an improved coin ejecting mechanism by which a coin is positively ejected from operative position after the door has been opened. By virtue of this construction it is impossible for a wet coin to stick in the passageways, a circumstance which frequently arises when gravity is relied upon to effect coin ejection.

A further object of the invention is to provide means for rejecting coins of smaller

size and denomination than the coin which should be used to operate the lock. This mechanism is preferably in the nature of a coin chute so constructed that the proper coins will be directed into operative position, and the smaller coins will be by-passed into the box without entering an operative position. A further feature is the arrangement by which the small coins will fail to operate the registering mechanism or the indicating mechanism of the lock, even if the coin should by accident reach operating position.

A further object of the invention is to provide a lock equipped with indicating or signalling mechanism, registering mechanism, mechanism for preventing the insertion of a coin while the compartment is occupied, spurious coin indicating mechanism, and rejecting mechanism for improper coins, so that the lock will be substantially foolproof in operation.

Further objects are to provide a lock of rugged durable construction, which is extremely unlikely to get out of order, which will be highly efficient in use, and which may be manufactured with comparative economy.

With the above noted and other objects in view, the invention consists in certain novel features of construction and combinations and arrangements of parts, as will be more fully hereinafter set forth and pointed out in the claims. The invention may be more fully understood from the following description in connection with the accompanying drawings wherein—

Fig. 1 is a view in front elevation showing the lock applied to a door.

Fig. 2 is a fragmentary view in rear elevation of the lock with the rear cover plate and the by-passing coin chute removed.

Fig. 3 is a complete view in rear elevation with the rear cover plate and coin chute removed, but showing the new position of the parts after the locking bolt has been retracted.

Fig. 4 is a view in vertical longitudinal section on the staggered line 4—4 of Fig. 2.

Fig. 5 is a fragmentary longitudinal sectional view on the line 5—5 of Fig. 2.

Fig. 6 is a transverse sectional view on the line 6—6 of Fig. 2.

Fig. 7 is a fragmentary transverse sectional view on the line 7—7 of Fig. 2.

5 Fig. 8 is a longitudinal detail view through the upper end of the lock casing showing the coin blocker in operative position.

10 Fig. 9 is a view in elevation of the indicator lever.

Fig. 10 is a fragmentary view in rear elevation of the lock, parts of the casing being broken away and in section for clearness.

15 Fig. 11 is a similar view, but showing the position of the parts when the inside knob has been turned to retract the bolt.

20 Fig. 12 is a fragmentary view in side elevation of the lock casing, showing the ends of the bolts and the window which exposes the register mechanism.

Fig. 13 is a detail view of the coin controlled operating arm 114 and associated mechanism.

25 It is to be understood that the accompanying drawings are merely illustrative of a preferred embodiment of the invention, and that they are not to be construed in a limiting sense.

Lock casing.

30 The lock casing is in the nature of a rectangular box, including a front wall 15, side walls 16, top and bottom walls 17, 18, and a removable rear wall 19. In attaching the lock casing to a door such as 20, the back plate 19 is first secured in position by the use of suitable securing devices such as the screws 21. The back plate carries at its upper corners, hook shaped lugs 22 adapted to engage with pins 23, projecting inwardly from the side walls 16 of the casing. At the lower corners of the plate 19 there are provided projections 24 having threaded sockets 25 therein for the reception of screws 26, 45 these screws passing through openings in lugs 27 fixed to the lower corners of the front wall of the box.

50 It will be noted that the lower front wall of the box is offset as at 28, and that this offset portion provides an opening 29 at the box front. Within the opening there is an inwardly projecting flange 30 adapted to serve as a seat for a removable plate 31. The projections 26 terminate flush with the 55 outer face of the flange 30. Secured to the rear face of the cover plate 31, adjacent the lower corners thereof, are a pair of hooks or lugs 32 adapted to engage behind the flange 30. The cover plate carries a lock casing 33 for a conventional type of tumbler lock shown in elevation at 34 (Fig. 1). The lock 60 34 is adapted to actuate a bolt 35 engageable with the upper portion of flange 30, whereby when the hooks 32 are engaged with the lower portion of the flange, and a suitable

key inserted to project the bolt 35, the heads of the screws 36 are concealed and it is impossible for one to remove the casing from the door by the use of a screw driver. Any unauthorized removal must be accompanied by the use of a key to retract bolt 35 to gain 70 access to the attaching screws 26.

The plate 31 in addition to its function as a concealing means for the screws, serves as the closure for the coin compartment, which 75 is constituted by the lower end of the box.

At the upper outer edge of the casing there is provided a coin reception slot 36 surrounded by a guiding device 37 for directing a coin into the slot 36. Secured to the 80 inner face of the front wall of the casing are a number of guide ways 38, 39 and 40 for the bolts, to be later described.

Bolts and keepers.

85 Slidable transversely of the casing between the guides 38 and 39 is a locking bolt 41, the end of said bolt being engaged by spring 42 mounted on a suitable supporting stud 43. This spring tends to normally 90 urge the locking bolt outwardly through an opening 44 (Fig. 12), in the side wall 16 of the casing. Mounted below the locking bolt 41 is a second bolt 45, sliding between the guide ways 39 and 40. The inner end of 95 this bolt is acted upon by a spring 46 mounted on a supporting stud 47, and normally urging the bolt to fully projected position through an opening 48 (Fig. 12) in the side wall of the casing.

100 The projecting ends of the bolts 41, 45 are bevelled as at 49 and 50 respectively for camming engagement with the edge 51 of a keeper. The keeper is in the nature of a casting 52 secured in any suitable manner as by lugs 53 passed through ears 54 to the frame 55 for the door 20. Preferably the keeper is cut away as at 56 for the reception of a guard plate 57 forming an extension of the front wall 15 of the lock casing, this guard plate preventing insertion of a sharp instrument into the keeper to forcibly retract the locking bolt.

105 The keeper is formed with a central web 58, and a roller 59 carries trunnions 60 turning in the web and in one end of the keeper, this roller being accommodated in a cut away portion 61 of the keeper.

110 When the door 20 is closed, the roller 59 always engages with the bolt 45 to retain the same in retracted position, and whenever the locking bolt 41 is retracted to permit the door to open, the bolt 45 will spring outwardly under the influence of its spring 46 as soon as it clears the roller 59. The means 115 for latching the locking bolt 41 in retracted position includes a pawl 62 pivoted on a stud 63 and formed with teeth 64 adapted to engage with a pin 65 projecting rearwardly from the bolt 41. The pawl is normally 120

125

130

135

140

145

150

155

urged into position to engage the pin 65 by a spring 66 anchored to a stud 67 and acting on a stud 68 projecting from a pawl operating extension 69. The extension 69 is curved 5 to offer a camming surface 70, against which a stud 71 on the bolt 45 bears when the bolt 45 is in retracted position. Thus, when the bolt 45 is retracted it swings the pawl 62 into the position shown in Fig. 2. Bearing in 10 mind the fact that the bolt 45 cannot be projected while the door is closed, and that the bolt 41 must be retracted in order to permit opening of the door, it will be seen that as the door is opened, with the bolt 41 re- 15 tracted, the bolt 45 springs outwardly, releasing extension 70 and permitting spring 66 to swing the teeth 64 into latching engagement with the pin 65. Conversely upon closing of the door, the roller 59 forces 20 the bolt 45 inwardly, acting through the stud 71 and extension 69 to trip the pawl and release the bolt 41.

The invention as thus far described is applicable to various types of locks other than 25 coin controlled locks. For instance I have shown a tumbler lock 72 secured to the front wall 15 of the lock casing, said tumbler lock being operated in a conventional manner by a key (not shown). This lock may include 30 a rotary element 73 carrying a crank arm 74 which engages in a notch 75 in the bolt 41 to effect retraction of the latter. Thus the bolt 45 serves to control the latching and releasing of the bolt 41 independently of the 35 other instrumentalities which may be utilized to retract the bolt 41.

Coin delivering and rejecting mechanism.

When a coin or token 76 is inserted through 40 the coin entrance slot 36, it enters an inclined coin chute 77. The upper end of the coin chute is spaced a slight distance below the slot 36 for a purpose which will be more fully hereinafter described. The coin chute includes ears 78 adapted to be secured to the front wall of the lock casing by screws or similar securing devices 79. Communicating with the lower end of the chute 77 is a vertical by-passing chute 80 adapted to 45 deliver coins directly into the lower end of the lock casing. Chute 80 as best seen in Fig. 10, includes a transversely disposed attaching arm 81. One apertured end of this arm is screwed as at 82 (Fig. 6) to a lug 83 projecting rearwardly from the face of the bolt guide 39. The other apertured end of the arm 81 is secured as by screw 84 to a bracket 85 projecting rearwardly from a bridging piece 86, this bridging piece being counter-sunk in the bolt guides 38, 39, and being accommodated in a cut out portion 87 (Fig. 2) of the locking bolt 41.

Between the coin chutes 77 and 80, there is interposed a transversely extending plate 88 having a selector slot 89 therein. It will

be noted that the lower wall of the chute 77 is cut away as at 90, but that such cutaway portion is of less length than the diameter of a coin for operating the lock. We may assume that the coin 76 which effects operation, is a nickel. In this instance the slot 89 will be of such a width that it will block the passage of nickels therethrough, and will permit the free passage of pennies. Thus, when a penny is inserted through the entrance opening 36, it will slide down the chute 77, pass freely through the slot 89 and be guided by the chute 88 directly into the bottom of the casing. When a nickel is inserted, it will pass down the chute 77 partially through the slot 89, where it will be checked by the end walls of said slot. The walls of the slot 89 serve as a flipping or turning device to turn the nickel over, and alter the path of its gravitational movement, so that it will slide over the guiding depending apron portion 90^a of the plate 88, will pass through a slot 91 in the bolt guide 38, and will enter a slot 92 in the locking bolt 41. This slot may be plainly seen 90 in Fig. 6, and it will be noted from Fig. 4 that the slot extends all the way through the locking bolt and through the bolt guiding member 39, so that when the coin reaches operative position, it rests upon the bolt 41. 95

From the foregoing description it will be seen that I provide means for delivering a proper coin into the operative position for controlling operation of the lock, as will be later described, and means for by-passing a 100 smaller coin directly to the bottom of the lock casing without effecting operation of any part of the mechanism.

Coin-controlled bolt-operating mechanism.

Projecting through the front wall of the casing and having bearings in the bolt guiding member 40, is a spindle 93 carrying an operating handle 94 at its outer end. At its inner end, the spindle carries a crank arm 95, from the free end of which a pin 96 projects forwardly into a slot 97 cut in the bolt 41. The crank arm may be connected to the spindle 93 in any convenient manner, as by screw 98, and a spring 99 acting on the crank arm and anchored to a stud 100 normally retains the crank arm swung to the position of Fig. 2, in which position the crank arm abuts against a stop shoulder 101 on the bolt guiding member 39. 110

The slot 97 in the bolt provides clearance for free turning movement of the crank arm to the right when there is no coin in place in the slot 92. By operating the handle 94, the crank arm 95 may be swung freely from the position of Fig. 2 to the position of Fig. 3 where it is stopped by the bracket 85. When a coin is in the operative position shown in Figs. 2 and 3 however, movement of the crank arm 95 to the right, causes the 115 120 125 130

pin 96 to engage with the coin, and by virtue of the coin engaging the right hand end of the slot 92, the lock bolt is retracted or shifted to the position of Fig. 2 through the intermediary of the coin.

It will thus be noted, that by inserting a coin into the lock, and turning the handle 94, the locking bolt 41 will be retracted, and as the bolt is held in retracted position, and the door bolt opened by the handle 94, bolt 45 will be released by its keeper roller 59, and will spring upwardly, thereby releasing the pawl 62 and permitting the pawl to engage the pin 65 on the locking bolt 41, whereby the locking bolt is held in retracted position.

When the user steps inside of the compartment controlled by the lock, and grasps the inner handle 103, closing the door after him, the bolt 45 will again be retracted as it engages the keeper roller 59, thereby engaging the tail piece of the pawl 62, and tripping the pawl to release the locking bolt 41 which will again spring into locking position.

25 *Coin displaying and ejecting mechanism.*

In Fig. 2 it will be seen that the bolt 45 has a slot 104 therein adapted to register with the slot 92 in the bolt 41. In order however, to prevent the loss of a coin by the accidental release of the handle 94 after the coin has been inserted and the handle turned to retract the bolt, I so arrange the slots 104 and 92 that they do not move into registration until after the door has been opened. In other words, as the door is opened and the bolt 45 is urged by its spring 46 to projected position, incidentally latching the retracted bolt 41, the slots 92 and 104 will register, and the coin will drop through the slots between a plate 105 and a window 106 in the front of the casing, at which point the coin is supported by a pin 107 until such time as another coin is inserted and the lock again operated.

By virtue of this construction, the last coin inserted will always be exposed through the window 106 and the attendant who is usually employed to take care of a number of coin controlled booths, will be offered a visible indication of any spurious coins or slugs which have been used to operate the lock. It will be noted that this indication will be available while the patron is still in the booth.

The pin 107 (Fig. 2) is carried by one arm 108 of a bell crank, the shorter arm 109 of which is fulcrumed on a stud 110 secured to the rear face of the plate 105. The elbow of the bell crank has a slot and pin communication 111 with the lower end of a link 112, said link being pivoted at its upper end as at 113 to an operating arm 114 which in turn is pivoted at 115 to the bolt guiding member 38. A coiled contractile spring 116

acting on the end of arm 108 and anchored to a stud 117 secured to the lower end of the plate 105, normally retains the bell crank in the position of Fig. 2. In this position the pin 107 is in operative position to prevent a coin from dropping below the window 106, and in this position also, the link 112 is pulled downwardly, and the operating arm 114 is depressed so that a camming extension 118 forming part of this arm is disposed in the path of a coin 76 resting on the bolt 45 in operative position to effect retraction of the bolt 41. The arm 114 is accommodated in the slot 91 of the bolt guide 38.

Assuming that one coin is in position before the window, as shown in Fig. 5, the insertion of a new coin, and the retraction of the locking bolt will serve to release said coin from its position before the window, and permit it to drop into the bottom of the casing. As the handle 94 is turned, shifting the locking bolt to retracted position, the coin 76 being engaged by the pin 97, will in turn engage with the camming extension 118 of the operating arm 114, lifting the operating arm, pulling the link 112 upwardly, and swinging the bell crank 108 to the position of Fig. 3 against the action of spring 116, whereby the coin supported on the finger 107 will be released.

In this connection it is to be noted, that if a coin should be sticky or moist and tend to adhere either to the glass window or to the plate 105, it will be positively ejected by an incoming coin. That is to say, the new coin dropping through the slots 92 and 104 will strike the coin before the window and tend to dislodge it, and if the coin is not dislodged by this action, it will be positively ejected as the corner 119 (Fig. 2) of the slot 104 engages the upper coin and exerts a downward camming action thereon.

55 *Manually-controlled bolt-operating mechanism.*

I have previously described the manner in which the lock may be opened by turning the outer handle 94 after the insertion of a coin, and the manner in which the locking bolt automatically snaps back to locking position when the door is closed and the patron enters a compartment. It is obviously necessary to provide some means for permitting the patron to open the door from the inside to gain egress from the compartment.

With this end in view, the knob 103 above mentioned, is connected to a spindle 120 having bearings in the back section 19 of the casing. The spindle at its inner end carries a crank arm 121 (Figs. 10 and 11), which may be formed with an extension 122 in the nature of a spring finger. Crank arm 121 is acted on by a spring 123 indicated in dotted lines in Fig. 1 as anchored to a stud

124 on the rear plate of the casing. This spring normally urges the crank arm 121 to the left, or to the position of Fig. 10 where it is stopped by lug 125 on the rear casing plate 19. As the knob 103 is turned to the right to shift the crank arm 121 to the position of Fig. 11, the crank arm engages with an ear 126 on the inner end of the locking bolt 41, whereby the bolt is manually retracted and the door may be opened. Closing the door after a patron has left the booth, effects resetting of the locking bolt in the manner above described.

15 *Registering mechanism.*

Secured to the side wall 16 of the lock casing as by screws 127, is a register 128 which may be of entirely conventional construction. The numeral wheels of this register are exposed through a window 129 in the casing wall. The operating lever 130 for the register 128 is connected by link 131 to an arm 132 of a bell crank including a second arm 133 pivoted as at 134 to the rear 25 face of plate 135. The elbow of the bell crank is connected by link 135 to a lever 136 fulcrumed at one end on a stud 137 secured to the front wall of the casing. Lever 136 is formed with a rearwardly extending block 30 or lug 138, to which the upper end of link 135 is pivotally connected. Lever 136 is engaged by an extension 139 of the operating arm 114 as this arm moves upwardly. Thus retracting of the locking bolt through the 35 intermediacy of a coin, lifts the arm 114, lever 136 and link 135. Link 135 acts through the bell crank 133, 132, and link 131 to swing the operating arm 130 of the register to the right and cause the device to register once.

There is a positive return for the register operating mechanism controlled through the intermediacy of the crank arm 121 operated by the inside handle knob 103. It is for 45 this purpose that I provide the spring finger 122 on the crank arm 121. Pivoted at 140 on a guide bracket 141 for the lever 136 is a bell crank including arms 142 and 143. The arm 143 carries a pin 144 adapted to be engaged by the finger 122 as the knob 103 is turned to the right, and the arm 142 engages the block or extension 138 on the lever 136 to positively effect depression of lever 136 and link 135.

50 As a patron leaves the compartment, he is compelled to turn the knob 103 in order to unlock the door, and as this knob is turned, the train of linkage for the register mechanism is reset.

60 *Indicating mechanism.*

The lever 136 which is shown in plan in Fig. 9, includes the enlarged end 145, formed with a shoulder 146 engaged by the extension 139 and operating arm 114. At this

enlarged end of the lever 136 there is displayed suitable indicia 147 seen in Figs. 1 and 9, and comprising the words "Vacant" and "Closed", or "Vacant" and "Occupied". The normal position of lever 136 is shown 70 in Fig. 2, and with the lever in this position, the word "Vacant" will appear through the window 148 in the front of the casing. When a patron inserts a coin, opens the door, and enters the compartment, the position of the lever will be shifted to that shown in Fig. 3 as above noted, and the "Closed" sign will appear at the window. When the patron leaves the compartment, and turns the knob 103, he effects not only resetting of 75 the registering mechanism, as above described, but resetting of the indicating lever 136 to again show the "Vacant" sign through the window 148.

80 *Coin blocker.*

Means is provided for preventing the insertion of a coin through the slot 36 when the compartment is occupied. This means includes a U-shaped yoke 149, the legs of 90 which are pivoted as at 150 on studs projecting laterally from the side walls of the coin chute 77. One leg includes a tail portion 151 curved for coaction with a camming roller 152 mounted on the block 138. The other leg of the yoke is acted upon by a light torsional spring 153 (Fig. 3) which serves to retain the yoke in the operative position of Fig. 4.

When, through the intermediacy of the 100 operating arm 114, the indicating lever and the block 138 are lifted, the roller 152 engages with one arm of the yoke 149 and swings the intermediate portion 154 of the yoke into position to effectively block the 105 insertion of a coin through the slot 36.

The return movement of the coin blocker to inoperative position is effected nonpositively; that is to say, the resetting mechanism which restores the indicating lever 110 136 to the position of Fig. 2, simply withdraws the roller 152 from engagement with the coin blocker and permits the light restoring spring 153 to act and return the coin blocker to the position of Fig. 4. It 115 will of course be understood that this spring is not powerful enough to reset the registering mechanism or the indicating lever, and that these mechanisms can be reset only through the positive action of the bell crank 142, 143. In connection with this bell crank, it may be noted that it is normally held in the position of Figs. 2, 3 and 10 by the action of an associated spring 155.

120 *Operation.*

It is believed that the operation of the locking mechanism will be entirely clear from the above detailed description, but it may be well to summarize the manner and 125

times at which the various parts of the mechanism are operated.

We will assume that the compartment is empty, that the indicating lever is in the position to show a "Vacant" sign, that the registering mechanism has been reset after its last operation, and that the door is closed. In this position the locking bolt 41 is projected and the bolt 45 is held in retracted 10 position by the roller 59.

A coin is inserted in the slot 36. If this coin is of improper denomination it drops through chutes 77 and 80 into the bottom of the box. If the coin is of the proper 15 nomination it drops through the chute 77, is flipped over by the plate 88 and guided into operative position in the slot 92, resting upon the bolt 41. The handle member 94 is now turned, causing the pin 93 to shift the coin 20 76 to the right in Fig. 2, thereby retracting the bolt 41. Simultaneously with the retraction of the bolt, the coin engages the camming extension 118 of the operating arm 114, and actuates the following mechanisms. 25 Pin 107 is shifted by its link 112 to release a coin before the window 106. The indicating lever 136 is swung to a new position, exposing a "Closed" sign through the window 148. Movement of this lever acts through 30 the roller 152 to move the coin blocker to operative position, closing the mouth of the entrance slot 36. Movement of this lever also acts through linkage 135, 133, 132 and 131 to actuate the register 128.

35 It will be borne in mind that all of these operations have been taking place as the locking bolt was being retracted and before the door has been opened. As the door is opened, the bolt 45 springs outwardly, permitting the coin to fall through the slot 104 in the position before the window 106. Outward movement of the locking bolt also 40 releases the pawl 62 which latches the locking bolt in retracted position. As the coin drops down through the slot 104, the operating arm 114 is released, and the spring 45 116 restores the pin 107 quickly so that it engages the new coin and holds it in place before the window.

50 At this time the coin blocker is still in blocking position, the indicating lever still shows a "Closed" sign, and the register has not been reset. The patron now enters the compartment and closes the door, whereupon roller 59 engages lever 45 which trips the pawl 62 and releases the locking bolt 41. The latter springs outwardly, and the door is again locked. No other mechanism is effected by closing the door.

60 When the patron grasps the knob 103 to open the door from the inside, the locking bolt 41 is again retracted by virtue of the engagement of the crank arm 121 with the lug 126. At this time also, finger 122 acts 65 through the bell crank 142, 143 to reset the

registering mechanism and shift the indicating lever so that the latter displays a "Vacant" sign at the window 148. This movement of the lever 136 permits the spring 153 to restore the coin blocker to inoperative 70 position out of the path of coins entering through the slot 36. As the patron leaves the compartment and closes the door, the bolts are relatched in the manner above described without affecting any of the other 75 mechanism.

Attention has been previously called to the rotating operating finger 74 which is operated by a key inserted in the lock 72, so that an attendant may gain access to the 80 compartment. Operation of the bolt by this lock does not affect the indicating mechanism, registering mechanism, or the coin holding pin 107.

In the event that a penny, by virtue of 85 slightly sticking to the coin chute 77, or in some other manner, should drop into the slot 92 in the locking bolt, the penny will function to permit opening of the lock. However, the penny cannot effect operation 90 of the indicating mechanism or registering mechanism because it will be too small to engage with the camming extension 118 of the operating arm 114. Furthermore this penny will be prominently displayed before 95 the window 106, and will be promptly discovered by an attendant.

Various changes and alterations might be made in the general form and arrangement 100 of parts described, without departing from the invention. Hence I do not wish to limit myself to the details set forth, but shall consider myself at liberty to make such changes and alterations as fairly fall within the spirit and scope of the appended claims. 105

I claim:

1. In a coin controlled lock, a locking bolt normally spring projected into locking position, means operative upon insertion of a coin for retracting said bolt, automatically 110 acting means for latching said bolt in retracted position, and means operative only after said bolt has been fully retracted and latched for shifting the coin to inoperative position.

2. In a coin controlled lock, a locking bolt normally spring projected into locking position, means operative upon insertion of a coin for retracting said bolt, automatically 115 acting means for latching said bolt in retracted position, and means operative only after said bolt has been fully retracted and latched for positively moving the coin to inoperative position.

3. In a coin controlled lock, a locking bolt, means operative upon insertion of a coin for retracting said bolt, means for latching said bolt only when the latter reaches fully retracted position, a second bolt controlling the latching means, and pre- 125 130

venting movement of a coin to inoperative position prior to the latching of said bolt.

4. In a coin controlled lock, a locking bolt, means operative upon insertion of a coin for retracting said bolt, a pawl for latching said bolt in retracted position, a second bolt acting on said pawl to normally retain the latter out of latching engagement with the locking bolt, said second mentioned bolt normally preventing movement of a coin to inoperative position, and permitting such movement only after the pawl has been released to latch the locking bolt.

5. In a lock of the class described, a lock casing adapted to be secured to a door and including a locking bolt, a handle at the outside of the door, adapted to act through the intermediacy of a coin to retract said bolt, a handle at the inside of the door, adapted to directly retract said bolt, registering mechanism including a train of levers actuated positively by the coin as the outside handle is turned to retract the bolt, and re-set positively as the inside handle is turned to retract the bolt.

6. In a lock of the class described, a lock casing adapted to be secured to a door and including a locking bolt, a handle at the outside of the door, adapted to act through the intermediacy of a coin to retract said bolt, a handle at the inside of the door, adapted to directly retract said bolt, registering mechanism, and signalling mechanism operated positively through the intermediacy of a coin as the outside handle is turned and reset positively by the inside handle as the latter is turned.

7. In a lock of the class described, a lock casing adapted to be secured to a door and including a locking bolt, a handle at the outside of the door, adapted to act through the intermediacy of a coin to retract said bolt, a handle at the inside of the door, adapted to directly retract said bolt, registering mechanism, and signalling mechanism operated positively through the intermediacy of a coin as the outside handle is turned and re-set positively by the inside handle as the latter is turned, the signalling mechanism including a signalling lever, and the registering mechanism including a train of operating levers actuated from the signalling lever.

8. In a lock of the class described, a lock casing adapted to be secured to a door and including a locking bolt, a handle at the outside of the door, adapted to act through the intermediacy of a coin to retract said bolt, a handle at the inside of the door, adapted to directly retract said bolt, registering mechanism, and signaling mechanism operated positively through the intermediacy of a coin as the outside handle is turned and re-set positively by the inside handle as the latter is turned, the signalling mechanism

including a signalling lever, and the registering mechanism including a train of operating levers actuated from the signalling lever, the means for operating the signalling lever from the outside handle including an operating arm engaged by the coin as the bolt is retracted.

9. In a lock of the class described, a lock casing adapted to be secured to a door and including a locking bolt, a handle at the outside of the door, adapted to act through the intermediacy of a coin to retract said bolt, a handle at the inside of the door, adapted to directly retract said bolt, registering mechanism, and signalling mechanism operated positively through the intermediacy of a coin as the outside handle is turned and re-set positively by the inside handle as the latter is turned, the signalling mechanism including a signalling lever, and the registering mechanism including a train of operating levers actuated from the signalling lever, the means for re-setting the signalling lever including a bell crank and operative connections between the inside handle and the bell crank.

10. In a coin controlled lock, a lock casing having an entrance opening for coins, a locking bolt sliding in said casing and having a slot therein, an operating handle, a crank arm attached to the operating handle and formed with a stud working in the slot, means for delivering coins from the entrance opening to the slot in the bolt, whereby the bolt may be retracted through the intermediacy of the coin as the handle is turned, a slotted member adapted to be brought into registration with a slot in the bolt after the latter has been retracted and to permit ejection of a coin, and a spring ejector finger acting on the coin to positively eject the same when the slots have been aligned.

11. In a device of the class described, a locking bolt, means acting through the intermediacy of a coin to retract said bolt, said casing having a window therein, means for passing the coin out of operating position into position before the window after the bolt has been retracted, and means for retaining the coin in position before the window until the bolt is subsequently retracted through the intermediacy of another coin.

12. In a device of the class described, a locking bolt, means acting through the intermediacy of a coin to retract said bolt, said casing having a window therein, means for passing the coin out of operating position into position before the window after the bolt has been retracted, and means for retaining the coin in position before the window until the bolt is subsequently retracted through the intermediacy of another coin, said retaining means including a spring finger supporting the coin before the window, and means operated, upon subsequent

14. A device of the class described in moving the finger aside and permitting the coin before the window to drop out of place.

13. A device of the class described in claim 12, wherein the incoming coin actuates the mechanism for releasing the coin before the window.

14. A device of the class described in claim 12, and including an ejector for positively ejecting a coin from operative position after the bolt has been retracted, and linkage connecting said ejector with the retaining pin. ¹⁰

FREDERICK W. KASSLER.
